UNITED STATES PATENT OFFICE.

FRED SPENCE, OF ALTRINCHAM, ENGLAND, ASSIGNOR TO LINOTYPE AND MACHINERY LIMITED, OF LONDON, ENGLAND, A COMPANY OF GREAT BRITAIN.

SHEET-DELIVERY MECHANISM OF PRINTING MACHINES.

Application filed February 28, 1922. Serial No. 539,979.

To all whom it may concern:

Be it known that I, FRED SPENCE, a subject of the King of the United Kingdom of Great Britain and Ireland, and residing at

5 Linotype and Machinery Works, Altrincham, in the county of Chester, England, have invented new and useful Improvements in or Relating to Sheet-Delivery Mechanism of Printing Machines, of which

10 the following is a specification.

This invention relates to sheet-delivery mechanism of printing machines, and particularly to that type of such mechanism which comprises a number of sticks supported by a carriage which is traversed inwards and outwards, the sticks, during the inward travel of such carriage, passing between delivery tapes from which during the subsequent outward travel of the carriage, 20 they receive the sheet. In this type of mechanism, as is well-known, the sheet is caused to fall on to the delivery board by the action of pivoted fingers which are raised and lowered between the sticks, and 25 which, when raised, engage the inner edge of the sheet and, as it were, sweep the sheet off the sticks during the inward travel of the carriage.

In this class of mechanism, considerable 30 difficulty has arisen through the breaking of the fingers, attributable, it is believed, to the violence with which they have been brought into contact with the stop which limits their movement to the inoperative position, and the object of the present invention is to provide means for arresting the fingers in their terminal positions with a minimum shock, and the preferred means for carrying this into effect dispense with all 35 such positive stops acting on the fingers, and impart to the said fingers a movement which gradually decreases in rate as the fingers approach their terminal positions.

The invention will now be described by 40 reference to the accompanying drawings in which:—

Figure 1 is a side elevation of sufficient of the delivery mechanism of a printing machine to illustrate the embodiment therein 45 of the said invention;

Figure 2 is a view similar to Figure 1, but showing the various parts of the mecha-

nism in positions respectively different from those occupied by them in such figure, and

Figure 3 is a plan of Figure 1 with parts omitted.

In these drawings, 1 indicates one of the several sticks which are secured to a shaft 2 supported by the carriage 3, only parts of which shaft and carriage are represented in the drawing. 5 indicates one of the several delivery tapes and 6 one of the tape rollers fast to a shaft 7, and between which rollers and tapes, the sticks 1 pass during the inward travel of the carriage 3, and from which they receive a sheet during each outward movement of said carriage.

8 are the sheet pusher fingers which are raised to erect position between the sticks 1 for pushing the sheets off the latter during the inward travel of the carriage 3, and lowered to prone position near the completion of that travel so as to be out of the path of the sheets as they are delivered on to the sticks during the next following outward travel of said carriage. 9 is the rock shaft on which the fingers 8 are adjustably secured, and which is supported in two brackets 10, horizontally adjustable along bars 11 at opposite sides of the machine, but only one such bracket and bar are represented in the drawings. The brackets 10 may be secured in their different adjusted positions by split pins 12 or equivalent, inserted into holes 13 in the said brackets and the bars 11. 85

All the foregoing means and their manner of operation are as is usual in existing delivery mechanism of a like kind, and the mechanism according to the present invention differs from those already known, in the respects hereinafter particularized.

Near one end of the rock shaft 9 is secured an arm 14 having a non-radial slot 15 with which engages a stud 16 fast to one arm 17 of a bell-crank lever 17, 18 pivoted to the adjacent horizontally-adjustable bracket 10. The other arm 18 of the lever 17, 18 has swivelled to it a perforated block 19 through which passes a pull-rod 20 on which it can be adjusted to any desired position, and secured by a pinching screw 21 in any such position, according to the different lengths of the sheets to be delivered. The outer end of the pull-rod 20 is pivot-

ally connected to a cam lever 22 pivoted to a bracket 23 fast to the respectively adjacent bar 11, and movable into and out of the path of a roller 24 mounted on the carriage 3 conveniently on the stick-carrying shaft 2. The bracket 10 has further pivoted to it, on a horizontal post 25, a curved lever 26 which is of such shape that it extends into the path of the roller 24, and this lever carries a downwardly-extending block or projection 27 which bears on the top of the lever arm 17. The horizontal post 25 is swivelled to the bracket 10 and through it loosely passes one end of a rod 28 whose opposite end is pivoted to the slotted lever arm 14. This rod 28 is encircled by a helical compression spring 29 which, at its respectively opposite ends, bears against the post 25 and a head or shoulder 30 on the rod 28, and the horizontal axes of the post 25 and the rock shaft 9 are so relatively positioned, as in certain toggle devices, that the spring 29 retains the fingers 8 in their two terminal positions until they are positively moved therefrom through the action of the roller 24 on either the curved lever 26 or the cam lever 22.

The operation of the before-described apparatus is as follows, it being, for convenience, assumed that the starting point of the cycle, is that at which the carriage 3 is at the end of its inward stroke, say approximately as shown in Figure 1 with the fingers 8 in their corresponding prone or inoperative position, as shown in the said figure, and held in that position, as hereinbefore explained, by the spring 29. During the next ensuing outward movement of the carriage 3, the sticks 1 receive a sheet from the tapes 3, the roller 24 passes over the then-depressed curved lever 26 without affecting it, and near the end of that outward movement, the said roller comes into contact with the cam lever 22 which, through the pull-rod 40, bell-crank lever 17, 18 and slotted arm 14, raises the fingers 8 to operative position, as shown in Figure 2. On the next inward journey of the carriage 3, the sheet is swept off the sticks 1, by the engagement of the fingers 8 with its inner edge, and the roller 24, during the continued inward movement of the carriage 3, depresses the curved lever 26, and this, through the block 27 thereon, turns the bell-crank lever 17, 18, so that the latter, through its stud 16, rocks the slotted arm 14 downwards, with the result that the fingers 8 are correspondingly swung downwards into their prone or inoperative position in which they are shown in Figure 1.

The swing of the fingers 8 from one position to the other, is limited by the outer end of the slot 15 contacting with the stud 16, and the angle and length of said slot are such that as the fingers 8 approach their terminal positions, their movement is gradually retarded, so that they are arrested in those positions without shock, and when they have reached said positions the axis of the slot and that of the lever arm 17 are perpendicular to each other, so that at those instants there is no turning moment about the axis of the finger-carrying shaft 9.

It is to be understood that the arrangement hereinbefore described and represented in the drawings, is to be regarded as illustrative merely of a preferred constructional form of the invention and that the same may be modified in many ways without departing from the essential features of such invention; for example, as will be obvious, the arrangement of the slot 15 and stud 16 may be reversed, that is to say, the former may be in the bell-crank lever arm 17 and the latter carried by the arm 14.

Having thus described my invention, I declare that what I claim and desire to secure by Letters Patent is:—

1. In or for sheet-delivery mechanism for printing machines, the combination of sheet-pushers fingers adapted to be swung about a horizontal axis, and an oscillating slotted arm for imparting such swinging motion, characterized by the fact that the slot is non-radial to the axis about which the arm oscillates.

2. In sheet-delivery mechanism for printing machines, the combination with a reciprocating delivery carriage and with devices according to claim 1, of means operated by the delivery carriage at different parts of its stroke to effect the swinging in relatively reverse directions of the sheet-pusher fingers.

3. In sheet-delivery mechanism for printing machines, means according to claim 2, characterized by a bell-crank lever turning about an axis in fixed relationship to that about which the fingers swing, and in sliding connection with the slot of the arm, two pivoted members such as 22 and 26 in position to be operated by the delivery carriage at respectively different parts of its stroke, and means connecting the said members with the bell-crank lever for moving it in respectively different directions.

In testimony whereof I have affixed my signature hereto.

FRED SPENCE.
